7 Claims. (Cl. 198—55)

1

This invention relates in general to housings and feed chutes therefor, and it finds particular application in housings and feed chutes of bucket elevators or conveyors such as are employed in elevating or conveying hot catalyst materials.

One object of the invention is to provide an improved elevator or conveyor structure in which the elevator or conveyor housing or casing is movable with respect to a relatively fixed feed chute, or vice versa.

Another object of the invention is to provide an improved structure as set forth in the foregoing object in which the members that slidably connect the casing or housing and the feed chute may be cleaned of materials such as catalyst particles which tend to lodge in or between them.

Another object of the invention is to provide an improved connecting mechanism by which, for example, an elevator or conveyor housing may be slidably connected with a feed chute or feed housing therefor and in which provision is made whereby abrasive materials that tend to lodge between and damage the connecting parts of the mechanism may be cleaned or removed from between the members by fluid under pressure.

Other and further objects of the invention will appear hereinafter, the novel features and combinations being set forth in the appended claims.

In the accompanying drawings,

Fig. 1 is a side elevational view of an elevator embodying features of the invention showing a portion of the guiding and supporting superstructure therefor;

Fig. 2 is a view on a larger scale of the lower portion of the elevator seen in Fig. 1;

Fig. 3 is a sectional elevational view on a larger scale through the feed chute seen in Fig. 2;

Fig. 4 is a sectional view on a larger scale, the view being taken on line 4—4 of Fig. 2 looking in the direction of the arrows;

Fig. 5 is a sectional view, the view being taken on line 5—5 of Fig. 4; and

Fig. 6 is a sectional view on a larger scale, the view being taken on line 6—6 of Fig. 1.

This application is a division of my co-pending application, Serial No. 700,928, filed October 3, 1946, now Patent No. 2,570,363, dated October 9, 1951, for a Bucket Elevator. It is to be understood that the construction and operation of the apparatus of this application follows that of my parent application above identified, and that only subject matter pertinent to the present invention is described herein in detail.

In Fig. 1 of the drawings there is illustrated an elevator or conveyor 10 that is employed for ele-

2

vating or conveying upwardly hot catalyst material that is fed into the elevator housing or casing 11 through a feed chute or feed housing 12 adjacent the bottom thereof. The catalyst flowing into the elevator housing or casing 11 is received by buckets of a chain and bucket conveyor apparatus, not shown, and is conveyed upwardly and discharged from the housing or casing 11 through a discharge chute 13 at the top thereof.

10 The chains of the conveyor mechanism travel over, and are driven by, a head shaft assembly including spaced wheels, not shown, that are carried upon a shaft 15 supported on bearings 16. Shaft 15 is driven from a motor and speed reducing drive mechanism indicated at 17. Within the bottom of the housing or casing 11 there is a floating foot shaft assembly 18 around which the chains of the conveyor travel and which is supported by the chains which travel in and are 20 guided by guides 14.

It may be mentioned that in the complete elevator unit the exterior surface of the housing or casing 11 includes a layer of insulating material which has not been shown in the drawings. This is because of the fact that the catalytic material is very hot, as a consequence of which there is a high temperature within the housing or casing 11 when the elevator is in operation. Because of the temperature differences which exist within the housing or casing 11 when it is in operation, as compared with when it is shut down, and particularly in view of the fact that the casing has appreciable height—for example, in one installation it is approximately one hundred seventy-five feet high, it is necessary to provide for the free expansion and contraction of said housing or casing 11, particularly along its length.

The supporting or suspending mechanism for the housing or casing 11 is in the form of a peripheral frusto-conical petticoat, skirt or flange 19 which is located near the top of said elevator and adjacent the bottom of the head section 20 thereof. The top of the skirt 19 is rigidly attached, as by welding, preferably around its entire periphery, to a supporting and reinforcing ring or belt 21, which in turn is rigidly attached to and forms a reinforcement of the periphery of the housing or casing 11. The bottom of skirt 19 rests upon a supporting superstructure 22 which includes a pair of spaced I-beams and interconnecting cross-beams that form a part of, or are attached to, a building or other independent supporting structure.

The entire load or weight of the casing 11, including the head section 20 of the elevator 10, is

supported by the superstructure 22 through the skirt 19 and ring 21. As a consequence of this fact, it is evident that the casing 11, including the head section 20, is rigidly connected to the external supporting superstructure 22 in only one horizontal plane which is the plane of connection of the skirt 19 and the ring 21, and consequently the casing 11 is free to expand without strain under the conditions of varying temperature which occur particularly between operating and non-operating conditions. For example, if the head section 20 expands it will expand upwardly from the ring 21. If the casing 11 below the ring 21 expands, it can expand downwardly therefrom since it is hanging free except for its connection to skirt 19 through ring 21.

In view of the height of the casing 11 it is desirable to provide guide means 23 at spaced vertical intervals to guide and brace said casing 11 against excessive lateral movement which, for example, may be caused by the wind, since in most installations these elevators are built outdoors and are merely supported by open frames, of which the superstructure 22 is a part. Details of one of these guide or anti-sway means 23 are shown in Fig. 6 of the drawings.

The guides 23 are below the supporting skirt 19, and they are provided by forming circumferential bands or belts 24, preferably constructed of angles, which belts 24 are rigidly attached to the casing 11 by welding. It may be pointed out that the casing 11 is preferably formed of a plurality of interconnected tubular sections which are bolted or welded together by top and bottom section flanges 25.

At spaced intervals around each belt 24 are upstanding guide bars 26 which are welded to the outwardly projecting legs of the angle belts 24 and which slidably extend into notches 27 formed in brackets or clips 28 mounted on channel members 29 of the superstructure 22, there preferably being guides 23 located at 90 degree intervals around the periphery of the casing 11 adjacent each of the belts 24. It is thus evident that the bars 26 are rigidly attached to the casing 11 and are free to slide upwardly and downwardly in the notches 27 of the brackets 28 which are rigid with the superstructure 22. These guides, of course, help brace the casing 11 and prevent undesirable lateral movement or twisting thereof under atmospheric influences or under the influence of the high temperature gases within said casing 11. It is to be noted that there is a small space or clearance between the outer edges of the bars 26 and the bottoms of the notches 27 of the brackets 28 that permits diametrical expansion of the casing 11. The above described support and guide means for the casing is claimed in my co-pending application, Serial No. 164,771, filed May 27, 1950, for a Bucket Elevator.

It may be mentioned that the elevator illustrated is employed in a hot catalyst oil cracking system and that the conveyor mechanism of it includes multiple compartment buckets carried between chains that convey both spent and regenerated catalyst, all as described in my parent application, Serial No. 700,928, now Patent No. 2,570,363, above identified.

Attention is now directed to Figs. 2 through 5 of the drawings and to the construction of the loading or feed chute 12. A number of problems have to be considered in connection with the construction of this feed chute. First of all, since the casing or housing 11 is subject to temperature variations, there is relative movement between it

and said feed chute or housing 12 in a substantially upright plane. In addition, the feed chute 12 is in effect three feed chutes or is a three-way or three-compartment chute, since the material flowing to the elevator is divided into three paths by said feed chute and delivered into three series of buckets or bucket compartments at the bottom of the elevator mechanism. In addition, individual control valves are provided for each of the separate chutes or chute compartments.

Said chute 12 includes laterally spaced and downwardly sloping side walls 30 between which is a pair of partitions 31. Adjacent their tops the partitions 31 converge so that they split the feed pipe or conduit 32 which carries the spent catalyst to divide it into two outside ways, troughs, chutes, or compartments in the multiple way feed chute 12. The central compartment trough or way of said chute 12 is fed by a regenerated catalyst pipe or conduit 33 and thus the regenerated catalyst flows centrally through the feed chute 12, with spent catalyst flowing on both sides thereof. The troughs or compartments of feed chute 12 are each provided with an individually operable control valve 34, each of which is controlled by an individual operating shaft and handle, not shown, which projects through the adjacent side of the trough. The central trough of feed chute 12 is provided with an individually controlled valve 35 also provided with an operating shaft and lever, not shown, that projects through one side wall of feed chute 12.

It is evident by reference to Figs. 2 and 3 of the drawings that the valves 34 and 35 are swingable about horizontal axes provided by their operating shafts and that said valves may be respectively opened and closed in variable amounts, being swingable upwardly behind stationary partition means 36 (see Fig. 3). The bottom plate 37 of the chute 12 is provided with three removable wear plates 38, one for each chute, said wear plates being removable as a unit with the upper portion of said bottom plate 37, said bottom plate 37 being split between its ends along the split line 39, as seen in Fig. 3 of the drawings.

The feed chute 12 also includes a vertical or upstanding frame or seal plate 40 which is rigidly attached to and forms a part of said chute 12. The lower portion of the chute ways is of reduced height as compared to the upper or feed portion, as clearly illustrated in Fig. 3 of the drawings, and this lower portion projects through a frame opening 41 formed in the foot or feed section of the casing 11. This lower reduced height portion of the chute 12 is free to move upwardly and downwardly in the opening 41 which has appreciably greater height than the adjacent height of the feed chute 12, thus providing for relative movement of the casing 11 with respect to the feed chute 12 with changing thermal conditions within casing 11.

The face of the opening 41 is provided with an upstanding seal or slide plate 42 having an opening 43 therein comparable in dimensions to the opening 41 through which the lower portion of chute 12 projects and with which it has relative up and down movement. Since the seal or slide plate 42 is fixed to and moves with the casing 11 and the frame or seal plate 40 is fixed to the chute 12, it is obvious that they will have relative sliding movement in an upright or vertical plane as the casing 11 expands and contracts and thus moves rectilinearly upwardly and downwardly with respect to chute 12.

To effectuate a seal for all relative positions

of plates 40 and 42, the plate 40 is provided along opposite sides with upper and lower guide brackets 44 (see Fig. 4) which are provided on their insides with notches 45 which receive interlocking outer edges of the plate 42. In addition, a spring-pressed seal or packing 46 is carried in a groove around the periphery of the seal plate 40 and is pressed against the seal plate 42, thus insuring an effective seal between the casing 11 and the feed chute 12 for all relative positions thereof.

In addition, to prevent abrasive material accumulating between the two plates 40 and 42 which might cause damage to the seal 46 or cause undue wear on either of them, a blowout pipe or conduit 47, which may be supplied with flue gas or other fluid or gas under pressure, communicates through spaced branch pipes or conduits 48 (see Figs. 4 and 5) to a transverse groove or conduit 41 formed adjacent the bottom of the plate 40 and above the bottom part of seal 46. By introducing fluid, such as air, flue gas and the like into the groove 41, abrasive material, such as catalyst dust, may be blown upwardly from the space between said plates 40 and 42.

To assist in the loading of the buckets, there is a loading plate 50 (see Fig. 3) located adjacent the discharge edge of the feed chute 12 which is essentially stationary with respect to casing 11 and is provided with three laterally spaced elongated windows or openings, one for each of the ways or compartments in the feed chute 12. The upper end of the loading plate 50 is rigidly connected to a bracket on the lower section of casing 11 (see Fig. 2), and the bottom is provided with a pair of pins 52 which extend through holes in brackets 53 attached to the bottom of the lower casing section 11, there being one adjacent each side. Since there may be some difference in thermal expansion of the loading plate 50 and the casing 11 to which it is attached, the pins 52 compensate for this by being readily slidable in the holes in brackets 53, while at the same time the loading plate 50 is held essentially rigid with the lower section of casing 11.

Directly above the feed chute 12 is an observation window 54. This window 54 makes it possible for an operator to view the material within the buckets of the elevator mechanism 10 without disturbing the enclosing character of the casing 11.

As previously mentioned, the casing 11 is made up of a plurality of vertically superposed and attached sections removably connected together by top and bottom flanges and is preferably provided with insulating material on its external surface. In the form of the elevator illustrated, the major portion of the casing 11 is suspended and hangs downwardly along an upright axis from its single support adjacent the belt 21 near its top, and it is guided at spaced intervals and held against lateral swinging by the guide or anti-sway means 23 which provide for its free expansion and contraction.

From the foregoing description it will be seen that by this invention there is provided an elevator or conveyer that includes an elongated casing or housing supported so that it may expand freely along its axis, particularly in response to temperature changes, which is connected slidably to a fixed feed chute or housing and that there is provided means for removing from between the parts that slidably connect the feed chute and elevator housing materials that would cause wear or otherwise damage them when the housing moves with respect to the feed chute.

It will, of course, also be seen that there is provided by this invention a simple and effective seal or connector mechanism for connecting two casings or housings so that one may move with respect to the other and which connector mechanism may be readily cleared or cleaned of abrasive materials which would cause wear or scratching of the parts of the connecting mechanism.

Obviously those skilled in the art may make various changes in the details and arrangement of parts without departing from the spirit and scope of the invention as defined by the claims hereto appended, and applicant therefore wishes not to be restricted to the precise construction herein disclosed.

Having thus described and shown an embodiment of the invention, what it is desired to secure by Letters Patent of the United States is:

1. An elevator for hot material including an elongated upstanding casing, means supporting said casing adjacent its top with substantially the entire casing hanging downwardly therefrom and suspended thereby, an endless elevator conveyer within said casing, a stationary feed chute for said conveyer including a chute extending into said casing near its bottom, means providing for vertical movement of said casing relative to said chute including a pair of relatively slidable frames, one connected rigidly to said chute, the other connected rigidly to said casing, a spring pressed seal between said frames, and conduit means for conducting fluid under pressure between said frames whereby material may be blown from between them.

2. An elevator for hot material including an elongated upstanding casing, means supporting said casing adjacent its top with substantially the entire casing hanging downwardly therefrom and suspended thereby, an endless elevator conveyer within said casing, a stationary feed chute for said conveyer including a chute extending into said casing near its bottom, means providing for vertical movement of said casing relative to said chute including a pair of relatively slidable frames, one connected rigidly to said chute, the other connected rigidly to said casing, and a spring pressed seal between said frames.

3. An elevator including an upstanding casing, means supporting said casing adjacent its top with the casing hanging downwardly therefrom and suspended thereby, an endless elevator conveyer within said casing, a feed chute for said conveyer including a chute extending into said casing near its bottom, means providing for relative vertical movement of said casing and feed chute including a pair of relatively slidable frames, one connected rigidly to said chute, the other connected rigidly to said casing, seal means between said frames, and conduit means for conducting fluid under pressure between said frames whereby material may be blown from between them.

4. An elevator including an upstanding casing, means supporting said casing adjacent its top with the casing hanging downwardly therefrom and suspended thereby, an endless elevator conveyer within said casing, a feed chute for said conveyer including a chute extending into said casing near its bottom, means providing for relative vertical movement of said casing and feed chute including a pair of relatively slidable frames, one connected rigidly to said chute, the other connected rigidly to said casing, and seal means between said frames.

5. In apparatus of the class described, the combination of a casing, of a chute extending into said casing, means providing for relative movement between said chute and casing including a pair of relatively slidable frames, one connected rigidly to said chute, the other connected rigidly to said casing, a spring pressed seal between said frames, and fluid means for blowing solid fine material from between said frames to prevent scratching thereof.

6. A feed mechanism adapted to be connected slidably to a casing having a feed opening therein whereby said casing may move with respect to said feed mechanism, said feed mechanism including slide frame means adapted to be carried by the casing in association with said feed opening therein, a feed chute adapted to feed material into said casing through said opening, seal frame means carried by said feed chute adapted to cooperate with said slide frame means, seal means between said slide frame means and said frame means, and conduit means for conducting fluid under pressure between said slide frame means and said seal frame means whereby material may be blown from between them.

15

20

25

7. A feed mechanism adapted to be connected slidably to a casing having a feed opening therein whereby said casing may move with respect to said feed mechanism, said feed mechanism including slide frame means adapted to be carried by the casing in association with said feed opening therein, a feed chute adapted to feed material into said casing through said opening, seal frame means carried by said feed chute adapted to cooperate with said slide frame means, and conduit means for conducting fluid under pressure between said slide frame means and said seal frame means whereby material may be blown from between them.

STANLEY M. MERCIER.
